Patented Jan. 31, 1967

206,842

INFRA-RED SPACE HEATER

Peter P. Surckla, Geauga County, Ohio, assignor to The Beitcher Manufacturing Corporation, Cleveland, Ohio, a corporation of Ohio

Filed Mar. 4, 1966, Ser. No. 1,295

Term of patent 14 years

(Cl. D81—19)

FIG. 1

FIG. 2

FIG. 3

FIG. 4

FIGURE 1 is a front elevation of such infra-red space heater;

FIGURE 2 is a perspective view of the infra-red space heater of FIGURE 1;

FIGURE 3 is a perspective view taken from below and showing an infra-red space heater embodying the design and modified as to length relative to the embodiment of FIGURES 1 and 2;

FIGURE 4 is an end elevation of the infra-red heater of either FIGURE 1 or FIGURE 3.

I claim:

The ornamental design for an infra-red space heater, as shown and described.
